Application January 15, 1946, Serial No. 641,277

14 Claims. (Cl. 62--122)

1

This invention relates to the production of oxygen by the liquefaction and rectification of air, and more particularly to the operation of the usual two-stage rectification system and associated heat exchangers.

All temperatures herein given are in degrees F. and pressures are in pounds per square inch gauge.

Oxygen is commonly produced by partial liquefaction of air and rectification at low temperatures; preferably rectification is conducted in two stages at different pressures. The refrigeration necessary for liquefaction is supplied to the air after it has been compressed and water-cooled to approximately room temperature, by indirect heat exchange with the effluent products of rectification. However, an additional amount of refrigeration must be supplied to compensate for cold losses resulting from the difference in enthalpy between the incoming air and the outgoing products of rectification and for heat leaks into the system. Methods of supplying this refrigeration heretofore used, involve compressing at least a portion of the incoming air to pressures as high as 3000 pounds and expanding with or without the performance of work to produce a temperature drop; or compressing all the incoming air to about 600 pounds and after the air has been partially cooled by the products of rectification expanding a portion of the air. These methods are wasteful from the standpoint of compressor energy and require a great deal of equipment in the form of extra compressors, intercoolers and expanders.

For economical operation, it is essential to recover the cold content of the outgoing products of rectification. This is usually accomplished by passing these products in heat transfer relationship with the incoming air. In older systems, in order to avoid deposition of frost and solid carbon dioxide in the tubular counter-current heat exchangers through which the air is passed in indirect heat exchange relation with the outgoing products of rectification, the air is treated in driers and caustic scrubbers to remove water and carbon dioxide prior to admittance of the air into the heat exchangers. Even with this treatment, the exchangers had to be thawed out regularly to remove the frost (which term is used in a generic sense to include both snow and ice) which caused stopping up of the apparatus.

More recently it has been suggested to use cold accumulators or regenerators (hereinafter referred to as heat exchangers) of large cold absorbing capacity through which the warm in-

2

coming air and the cold products of rectification are alternately passed with periodically reversed operation so that streams of warm air are flowed through the same packing-filled spaces that the cold separated oxygen and nitrogen traversed during the previous step in the process, the high-boiling impurities deposited in these spaces during the passage of air therethrough being removed by sublimation during the subsequent flow in a reverse direction of the products of rectification. The use of these reversing heat exchangers in a process in which the air is compressed to relatively high pressure results in more costly operation from the standpoint of horsepower requirements because upon every reversal, which may take place every three minutes, the volume of compressed air in the heat exchangers is lost and must be again replaced. Also in the operation of these reversing heat exchangers containing packing-filled spaces through which the gases flow, undue dilution takes place of (a) a compressed air stream flowing to the rectification system with nitrogen, and (b) the nitrogen stream with air, which dilution necessarily occurs upon each reversal of flow, causing the air stream to flow through the packing-filled spaces containing nitrogen, and the nitrogen stream to flow through the packing-filled spaces containing air, left therein from the streams of nitrogen and air, respectively, passed therethrough during the preceding step of the process.

Copending application Serial No. 632,858, filed December 5, 1945, discloses and claims a process for producing oxygen by liquefaction and rectification of air involving the flow of air at about 70° to about 85° pounds at a temperature of about 70° to about 110° F. through the heat exchange paths of two or more reversing heat exchangers in series, each exchanger containing two other paths through which are passed, respectively, streams of oxygen and nitrogen products of rectification, in heat exchange relation with the air passing therethrough. One of the streams flowing between the first exchanger and a second exchanger is refrigerated either by an external refrigerant or by expanding a minor portion of the total air introduced into the process, say from 5% to 10% by volume, preferably about 7%, to produce refrigeration which is imparted either to the remainder of the air prior to its flow through the second exchanger or to the rectification products prior to their flow through the first heat exchanger, the amount of cold thus introduced into the process being adequate

to compensate for cold losses resulting from the difference in enthalpy between the air introduced into and the products of rectification withdrawn from the process and for heat leaks into the system. The temperature conditions in the first exchanger are such that substantially all moisture present in the air is removed therefrom in the form of frost. The temperature conditions in the second exchanger are such as to effect substantially complete removal of carbon dioxide from the air in its passage therethrough.

At the colder end of the second exchanger where the oxygen and nitrogen products of rectification enter and air leaves the exchanger, there is maintained between these products of rectification and the countercurrent stream of air a temperature difference in the range of about 5° to about 10° F., preferably about 6° to about 8° F. This temperature difference is the difference between the temperature of the air and the weighted average temperature of the products of rectification, all temperatures being taken at the colder end of the second exchanger. The weighted average temperature of the products of rectification is calculated by multiplying the temperature of the oxygen product stream by the volume percentage of the stream based on the combined volume of the products of rectification and adding thereto the corresponding figure obtained by multiplying the temperature of the nitrogen product stream by its volume percentage. Thus, for example, if the rectification system is operated to produce two streams of substantially pure oxygen and pure nitrogen, the weighted average temperature of the two streams would be approximately the sum of 20% of the oxygen stream temperature and 80% of the nitrogen stream temperature. Periodically the flow of air and nitrogen through their respective paths in the two exchangers is reversed so that upon reversal the air flows through the paths in the two exchangers through which during the preceding step the nitrogen had passed, and the nitrogen flows through the paths in the two exchangers through which had previously passed the air. The nitrogen removes, by sublimation, the carbon dioxide deposited during the preceding step in the second exchanger and the frost deposited during the preceding step in the first exchanger.

Operating in this manner, complete purging of carbon dioxide is attained upon each reversal of flow. Likewise complete purging of frost is obtained so that the equipment may be operated continuously.

Copending application Serial No. 632,859, filed December 5, 1945, discloses and claims a process which combines with the process of the aforesaid application Serial No. 632,858 involving the feature of refrigerating one of the streams flowing from the first exchanger to a second exchanger, the amount of cold thus introduced into the process being adequate to compensate for cold losses resulting from the difference in enthalpy between the air introduced into and the products of rectification withdrawn from the process and for heat leaks into the system, and maintaining at the colder end of the second exchanger where the oxygen and nitrogen products of rectification enter and air leaves the exchanger, a temperature difference between the air and the weighted average temperature of the nitrogen and oxygen from about 5° to about 10° F., preferably about 6° to about 8° F., the feature of effecting the removal of incondensibles such

as hydrogen, helium and neon from the rectification system without substantial reduction in the yield of oxygen recovered in the process. Thus, in accordance with the invention of said application Serial No. 632,859, a stream of air at about 70 to about 85 pounds and a temperature of about 70° to about 110° F. is passed through the heat exchange path of two heat exchangers in series, each of the heat exchangers containing at least three paths in heat exchange relation with each other, and streams of oxygen and nitrogen products of rectification are passed through two other paths in the heat exchangers in heat exchange relation with the air passing therethrough. At least one of the streams, preferably the air stream, is cooled during its flow from one heat exchanger to the other, the amount of cold thus introduced into the process being adequate to compensate for cold losses resulting from the difference in enthalpy between the air introduced into and the products of rectification withdrawn from the process and for heat leaks into the system. The flow of air and nitrogen and oxygen into and from the second heat exchanger is regulated so that the difference between the temperature of the air and the weighted average temperature of the nitrogen and oxygen at the colder end of the second exchanger is about 5° to about 10° F., preferably about 6° to about 8° F., thereby effecting complete removal of carbon dioxide from the air in its passage through the second exchanger.

The air from the heat exchangers flows to the high pressure stage of a two-stage rectification system in indirect heat exchange relation with the rectification products from the low pressure stage. From about 1% to about 15% by volume of the total nitrogen introduced into the process, which nitrogen contains incondensable gases, is withdrawn from the high pressure stage, preferably about 10% of the nitrogen thus withdrawn is heated and mixed with the remaining 90%, thereby yielding a nitrogen stream having a temperature sufficiently high to avoid formation of liquid nitrogen upon the subsequent expansion of this nitrogen stream. After expanding the nitrogen stream to lower its temperature, the expanded nitrogen stream is passed in heat exchange relation with oxygen and nitrogen streams supplied as reflux to the low pressure stage, and with the air supplied to the high pressure stage, thereby cooling the reflux liquids and improving the efficiency of the operation of the rectification system.

Periodically, the flow of air and nitrogen through their respective paths in the two heat exchangers is reversed, the air, upon reversal flows through the paths through which had previously flowed the nitrogen and the nitrogen flows through the paths through which had previously flowed the air, so that upon each reversal the nitrogen substantially completely removes the carbon dioxide deposited in the second exchanger and the frost deposited in the first exchanger during the preceding step of the process.

The processes of the aforesaid copending applications represent a substantial and important advance in the art of producing oxygen by the liquefaction and rectification of air, over prior procedures.

This invention is in the nature of an improvement on the processes of these applications. Among the objects of this invention is to still further minimize power losses occasioned by reversal of flow through the heat exchangers,

each reversal, as noted above, resulting in a loss of the volume of compressed air in the exchangers which must be replaced, and to also minimize dilution of the compressed air stream with nitrogen and the nitrogen stream with air, and still obtain, upon each reversal of flow, substantially complete removal of frost and carbon dioxide deposited in the exchangers during the preceding step of the process, without the use of chemical reagents, so that the process may be operated continuously. Other objects and advantages of this invention will be apparent from the following detailed description thereof.

According to the present discovery, a stream of air at about 70 to about 85 pounds gauge and a temperature of about 70° to about 110° F. is passed through a reversing heat exchanger zone in heat exchange relation with streams of oxygen and nitrogen products of rectification, the air being cooled to a temperature at which substantially complete removal of moisture therefrom is accomplished. The air then flows through a second zone or exchanger of the non-reversing type or one which is reversed only infrequently, say at periods of about a week's time, passing therethrough in heat exchange relation with oxygen and nitrogen products of rectification which flow from this exchanger to the first-mentioned exchanger. The rate of flow of the air and the oxygen and nitrogen products of rectification through this second or intermediate exchanger zone is controlled so that the temperature of the air at the colder end of this exchanger is within the range of -180° to -210° F., preferably about -195° to -205° F. One of the streams flowing between the first exchanger zone and this intermediate or second exchanger zone is refrigerated, the amount of cold thus introduced into the process being adequate to compensate for cold losses resulting from the difference in enthalpy between the air introduced into and the products of rectification withdrawn from the process and for heat leaks into the system.

The air from the second zone or intermediate exchanger flows through another zone or reversing exchanger in heat exchange relation with the oxygen and nitrogen products of rectification, the flow through this exchanger or zone being controlled so that the difference between the temperature of the air and the weighted average temperature of the oxygen and nitrogen at the colder end of this exchanger is in the range of about 5° to about 10° F., preferably about 6° to about 8° F., the temperature conditions in this exchanger being such as to effect substantially complete removal of carbon dioxide from the air in its passage therethrough.

The air from the second reversing exchanger is passed to the high pressure stage of a two-stage rectification system in indirect heat exchange relation with rectification products from the low pressure stage of this system. Preferably from about 1% to about 15% by volume of the total nitrogen introduced into the process, which nitrogen contains incondensable gases, is withdrawn from the high pressure stage of the system, and after heating, if desired, as hereinabove disclosed, expanded and passed in heat exchange relation with nitrogen and oxygen streams fed to the low pressure stage and air fed to the high pressure stage.

Periodically, the flow of air and nitrogen through their respective paths in the two reversing heat exchangers is reversed so that upon reversal, the air flows through the paths in the two

exchangers through which, during the preceding step, the nitrogen had passed and the nitrogen flows through the paths in the two exchangers through which had previously passed the air; no such reversal of flow takes place through the second or intermediate exchanger during the normal operation of the process. The nitrogen removes, by sublimation, the carbon dioxide deposited during the preceding step in the second reversing exchanger and the frost deposited during the preceding step in the first reversing exchanger. Operating in this manner, complete purging of carbon dioxide and frost is obtained upon each reversal of flow, so that the equipment may be operated continuously and the volume loss upon each reversal of flow is less than in the processes of the aforesaid pending applications, by an amount equal to the volume of the intermediate or second exchanger. Thus power losses are minimized; also dilution of the compressed air stream with nitrogen and the nitrogen stream with air is reduced.

In the preferred embodiments illustrated in the drawings, Fig. 1 shows diagrammatically a preferred layout of apparatus for practicing the process of this invention in which the air stream flowing from the first reversing heat exchanger to the intermediate exchanger is cooled by an external refrigerant and provision is made for effecting the removal of incondensibles, such as hydrogen, helium and neon from the rectification system; and Fig. 2 shows diagrammatically a preferred layout of apparatus for practicing the process of this invention in which refrigeration is supplied to the air stream flowing from the first reversing exchanger to the second reversing exchanger by expanding a portion of this air stream and passing the expanded portion of the air in heat exchange relation with the remainder, and the rectification system is designed to effect removal of incondensable gases. It will be understood, however, that the process of this invention may be carried out in other equipment; for example, the method of Fig. 2 of applying refrigeration to the air stream flowing from the first reversing exchanger to the second may be used instead of that of Fig. 1 in the layout of equipment shown in Fig. 1, and vice versa, i. e., the external refrigerant method of Fig. 1 may be used instead of that shown in Fig. 2, with the equipment shown in Fig. 2. Moreover, each of the reversing exchangers and the non-reversing exchanger may be replaced by two or more smaller exchangers placed in series and/or parallel, if desired, although this is objectionable from the standpoint of increasing construction costs, or the number of heat exchange paths may be increased over the three-path construction shown in the drawings, or other refrigeration systems may be employed in lieu of those disclosed in the drawings. Hence, the scope of the invention is not confined to the embodiments herein described.

In Fig. 1, reference character 10 indicates a heat exchanger which may be of any well known type. In the embodiment shown on the drawings, it consists of a single shell in which are provided three paths, namely, interior path 11 through which flows in one and the same direction throughout the operation of the exchanger the oxygen product of rectification. Paths 12 and 13 are provided within the shell of exchanger 10 through which periodically flow air and the nitrogen product of rectification in heat exchange relation with each other and with the oxygen. The

heat exchanger has in each of the paths suitable fins of heat-conducting material, e. g., copper, promoting rapid and efficient heat exchange between the gaseous media flowing therethrough. As the construction of the heat exchanger per se does not form part of this invention and as it may be of any well known type, it is believed further description thereof is unnecessary.

The flow of the air and nitrogen through their respective paths is periodically reversed so that during one step of the process air flows through path 12 and nitrogen through path 13, and upon reversal, during the succeeding step, air flows through path 13 and nitrogen through path 12.

Reversal of flow is accomplished by suitably positioning the compound reversing valves 14 and 15 which may be of any well known type. Valve 14 is disposed in the pipe line system consisting of air inlet pipe 16 leading into valve 14, and pipe lines 17 and 18 leading from the valve to paths 12 and 13, respectively. At the other end of the heat exchanger 10, lines 19 and 20 are positioned leading from paths 12 and 13, respectively, to the valve 15.

A substantially non-reversing heat exchanger 1 is provided in the form of a shell having therein paths 2, 3 and 4 provided with fins to promote heat exchange, as in the case of the exchanger 10. Path 2 is the path through which the oxygen product of rectification flows. Paths 3 and 4 are for the flow of air and the nitrogen product of rectification, respectively, in heat exchange relation with each other and with the oxygen.

A refrigeration system 32 of any well known type for supplying a refrigerating medium such as ethylene or carbon tetrafluoride is provided for cooling either the nitrogen or oxygen flowing from heat exchanger 1 to heat exchanger 10, or the air flowing from heat exchanger 10 to heat exchanger 1. This refrigerating system operates to cause the flow of the refrigerating medium in indirect heat exchange relation with the nitrogen, oxygen or air to be cooled, the rate of flow and temperature of the various media being so controlled that enough cold is introduced by refrigeration at this point in the process to compensate for cold losses resulting from the difference in enthalpy between the incoming air and the outgoing products of rectification and for heat leaks into the system.

Preferably, the air leaving the heat exchanger 10 is refrigerated to cause a drop of about 5° to about 10° F. in its temperature; this has been found adequate for the purposes above stated. Refrigeration of the air is accomplished by causing it to flow through pipe line 33, which passes through the refrigerator 32 in indirect heat exchange relation with the refrigerant; pipe line 33 communicably connects valve 15 with path 3 of heat exchanger 1 through which path the air flows. Line 9a is the nitrogen line connecting the nitrogen path 4 of heat exchanger 1 with the valve 15 and 25a is the oxygen line connecting oxygen path 2 of heat exchanger 1 with the oxygen path 11 of heat exchanger 10.

A second reversing heat exchanger 21 is provided in the form of a shell having therein paths 22, 23 and 24 provided with fins to promote heat exchange as in the case of exchangers 1 and 10. Path 24 is the path through which the oxygen product of rectification flows from the rectification system, hereinafter described, to pipe line 25, which communicates with oxygen path 2 of heat exchanger 1. At one end, paths 22 and 23 of heat exchanger 21 communicate with pipe lines

26 and 27, respectively, which are communicably connected with a compound valve 28 provided with a line 33a leading from path 3 of heat exchanger 1 and a second line 9 leading into the path 4 of heat exchanger 1. At the other end, paths 22 and 23 communicate, respectively, with lines 29 and 30, which in turn communicate with a compound reversing valve 31 which may be of the same type as the other reversing valves. Reversing exchangers 10 and 21 and the substantially non-reversing exchanger 1 may be placed in vertical, horizontal or any other desired position. Moreover, when these exchangers are arranged vertically, the colder end may be above or below the warmer end, i. e., the arrangement of flow therethrough may be reversed so that instead of the air flowing downwardly and the oxygen and nitrogen upwardly, as in the case of exchanger 10, the air may flow upwardly and the oxygen and nitrogen downwardly, similar reversal of flow taking place in the other exchangers.

With the arrangement of valves and piping shown, flow of nitrogen and air through heat exchangers 10 and 21 may be periodically reversed, say every three minutes, while no reversal of flow takes place through heat exchanger 1, so that during an initial period of operation, air flows through heat exchange path 12, through line 19, valve 15, refrigeration system 32 by way of line 33, path 3 in heat exchanger 1, line 33a, valve 28, line 26, cooling path 22 in heat exchanger 21, pipe line 29, valve 31, and thence to line 34 leading through the non-reversing heat exchanger 35 to the rectification system herein-after described. At the same time, nitrogen flows through pipe line 36 leading from the non-reversing heat exchanger 35 into valve 31, line 30, through path 23 in heat exchanger 21, through line 27, valve 28, line 9, path 4 in heat exchanger 1, line 9a, valve 15, line 20, path 13 in heat exchanger 10, leaving this path through pipe line 18 and passing through valve 14 to the atmosphere or other suitable disposal point. Upon reversal (as shown by dotted arrows and valve settings), the air flows through valve 14, line 18, path 13 in heat exchanger 10, line 20, valve 15, refrigeration system 32 by way of line 33, path 3 in heat exchanger 1, line 33a, valve 28, line 27, path 23 in heat exchanger 21, line 30, valve 31 and pipe line 34, into the non-reversing heat exchanger 35. At the same time, the nitrogen flows from heat exchanger 35 to pipe line 36 into valve 31, line 29, path 22 in heat exchanger 21, line 26, valve 28, line 9, path 4 in heat exchanger 1, line 9a, valve 15, line 19, into path 12 in heat exchanger 10, thence through line 17 into valve 14, and thence to the atmosphere or other suitable disposal point.

The rectification system comprises a two-stage rectification column 37, the lower section 38 of which is operated at a pressure of about 72 pounds gauge and the upper section 39 of which is operated at a pressure of from about 4 pounds to about 10 pounds gauge, preferably at about 5 pounds gauge. This column as is customary is provided with rectification plates of the bubble-cap or other desired type. The lower section 38 of the column 37 communicates with a condenser 40 and has a liquid collecting shelf 41 disposed immediately below the condenser 40 for collecting liquid nitrogen. Pipe line 42 leads from this shelf 41 to a non-reversing heat exchanger 43 which in turn communicates through a pressure reducing valve 44 with the top portion of the upper section 39, as indicated by the reference char-

acter 45. Condenser 40 acts as a reboiler for the upper section 39 of the column 37.

From the base portion of the lower section 38, a pipe line 46 for the flow of crude oxygen (containing approximately 40% oxygen) passes to a non-reversing heat exchanger 47 which communicates through pipe line 48 having a pressure reducing valve 49 therein with the low-pressure section 39 at an intermediate point indicated by the reference character 50. A line 51 having a pressure reducing valve 52 therein, leads from condenser 40 to a nitrogen line 58 leading to the non-reversing heat exchanger 35. A line 54 leads from the top of low-pressure column 39 to the heat exchanger 43, the nitrogen flowing through this line passing through the heat exchanger 43 then through line 55 and heat exchanger 47 into line 56 which communicates with heat exchanger 35. An oxygen line 57 leads from the lower part of the low-pressure section 39 of column 37 to path 24 of heat exchanger 21. The heat exchangers 35, 43 and 47 and the two-stage fractionating column 37 may be of any conventional type. Two separate fractionating columns, suitably interconnected, may be used in place of the two-stage column 37 shown. It will be understood that the equipment throughout is heat insulated to minimize loss of cold.

A desirable operating range involves the introduction of air at a pressure of 70 to 85 pounds gauge and at a temperature of 70° to 110° F. into path 12 or 13, as the case may be, in heat exchanger 10, the air leaving this path at a temperature of -120° to -150° F. and substantially the same pressure. The nitrogen and oxygen products of rectification enter the heat exchanger 10 at a temperature of -127° to -162° F. and leave at a temperature of 60° to 100° F. The air, in passing from heat exchanger 10 to heat exchanger 1, is refrigerated from 5° to 10° F. so that it enters heat exchanger 1 at a temperature of -125° to -160° F. The air leaves this heat exchanger 1 at a temperature of -180° to -210° F.; the oxygen enters heat exchanger 1 at a temperature of -183° to -213° F. and leaves at a temperature of -127° to -162° F.; the nitrogen enters this heat exchanger at a temperature of -183° to -213° F. and leaves at a temperature of -127° to -162° F. The air enters heat exchanger 21 at a temperature of -180° to -210° F. and leaves at a temperature of -260° to -280° F. The oxygen enters heat exchanger 21 at a temperature of -288° to -293° F. and leaves at a temperature of -123° to -213° F.; the nitrogen enters heat exchanger 21 at a temperature of -265° to -285° F. and leaves at a temperature of -183° to -213° F. The several streams suffer only a small pressure drop in flowing through the exchangers 10, 1 and 21.

One example of the operation of the process of this invention in the layout of equipment shown in Fig. 1 is described below. It will be understood this example is given for purposes of exemplification only, and the invention is not limited thereto.

Air under pressure of about 75 pounds and at a temperature of about 100° F. is supplied through line 16, valve 14 and line 17 to heat exchanger 13 flowing through path 12 in which it is cooled to a temperature of -134° F. The air then flows in indirect heat exchange relation with ethylene in the refrigeration system 32 and is cooled thereby to a temperature of -142° F., passes through the path 3 of the heat exchanger 1, leaving this path at a temperature of -200° F., and then

passes through path 22 of the heat exchanger 21, leaving this path at a temperature of -273° F. Substantially all moisture is removed in the form of frost in path 12 of heat exchanger 10 and all carbon dioxide is removed in solidified form in path 22 of heat exchanger 21; no appreciable removal of condensable material takes place in heat exchanger 1. From heat exchanger 21 the air flows through the non-reversing heat exchanger 35 in heat exchange relation with nitrogen and enters high pressure column 38 at a temperature of -275° F. and a pressure of 72 pounds.

Crude oxygen at a temperature of -278° F. and a pressure of 72 pounds leaves the base of column 38, flows through the heat exchanger 47 where its temperature is reduced to -286° F. and, upon flow through the pressure reducing valve 49, is flashed, entering low pressure column 39 at a temperature of -310° to -315° F. and at a pressure of 5 pounds. Pure oxygen is withdrawn through line 57 at a temperature of -292° F. and a pressure of 5 pounds, and flows through path 24, its temperature being increased to -203° F. The oxygen at this temperature passes through path 2 of heat exchanger 1 where its temperature is increased to -144° F., flows through path 11 of heat exchanger 10 and is withdrawn from this path at a temperature of 90° F. and at a pressure of one pound.

Nitrogen, at a temperature of about -286° F. and a pressure of 72 pounds, is withdrawn through line 51 and passes through valve 52, its temperature being reduced to about -315° F. as a result of the expansion through the pressure reducing valve 52. Nitrogen, at a temperature of -315° F. and a pressure of 5 pounds, is also withdrawn from the top of low pressure column 39 through line 54 and flows through heat exchanger 43 where its temperature is raised to about -304° F. The nitrogen flows from heat exchanger 43, through heat exchanger 47 and mixes with that from line 51. The nitrogen stream thus produced at a temperature of -294° F. flows through line 56 into the heat exchanger 35 where the temperature of the nitrogen is raised to -278° F. The nitrogen at this temperature and a pressure of about 5 pounds enters path 23, flowing therethrough in heat exchange relation with the oxygen which enters at a temperature of -292° F. and the air which enters the opposite end of heat exchanger 21 at a temperature of -200° F. The nitrogen leaves path 23 at a temperature of -203° F. At the colder end of the heat exchanger 21, the nitrogen and the oxygen streams have a weighted average temperature of about -281° F., while at this point the air is at a temperature of -273° F. A temperature difference of about 8° F. is, therefore, maintained. From the heat exchanger 21, the nitrogen flows through line 27, reversing valve 28, line 9, entering path 4 of heat exchanger 1 at a temperature of -203° F. and leaving at a temperature of -144° F. It flows through line 9a, valve 15, into and through heat exchanger 10, entering path 13 of this heat exchanger at a temperature of about -144° F. and leaving at a temperature of 90° F. and a pressure slightly above atmospheric, say one pound.

Upon reversal (as shown by dotted arrows and valve settings), which may take place every three minutes through the heat exchangers 10 and 21, the air flows through the paths 13 and 23, respectively, of heat exchangers 10 and 21, and nitrogen flows through paths 12 and 22, respectively, of heat exchangers 10 and 21; the air and nitrogen

flow, respectively, through paths 3 and 4 of heat exchanger 1, no reversal of flow through these two paths taking place. The flow is otherwise substantially the same, and the temperature and pressure conditions remain the same. The nitrogen in its flow through path 22 of heat exchanger 21 removes by sublimation the carbon dioxide deposited in this path by the air during the preceding step. Likewise, the nitrogen in its flow through path 12 of heat exchanger 10 removes from this path the frost deposited therein by the air during the preceding step. Thus, in the continued operation, upon each reversal, the nitrogen effects removal of the frost and carbon dioxide deposited in the paths of heat exchangers 10 and 21 through which the air has passed during the preceding step of the process.

The layout of apparatus shown in Fig. 2 differs from that of Fig. 1 chiefly in that, instead of the refrigerator 32, an expander and associated piping is employed to impart refrigeration to one of the streams flowing between heat exchanger 10 and heat exchanger 21, and the rectification system 37 is designed to effect removal from the high pressure stage of incondensable gases by expansion of a minor portion of the nitrogen containing such incondensable gases, and employing the expanded nitrogen to supply refrigeration to the nitrogen and oxygen streams employed as reflux in the low pressure stage of the rectification system, preferably also to supply refrigeration to the air introduced in the high pressure stage of the rectification system, thus increasing the efficiency of the operation of the rectification system.

Corresponding parts in Figs. 1 and 2 have been given like reference characters, and it is believed the construction and operation of these parts will be apparent from the above description thereof.

From the heat exchanger 10, the compressed air flows through valve 15 and line 33, the major portion of the air flowing through this line into the zone 3 of heat exchanger 1. A minor portion, say from 5% to 10% by volume, preferably about 7%, the exact amount being controlled by the setting of valve 6 in line 5, flows through line 5 into an expansion engine or turbine 7 hereinafter referred to as an expander. The air leaving the expander 7 at a lower pressure and temperature flows through line 8 into line 9 where it mixes with the nitrogen stream flowing through this line from valve 28, the resultant mixture flowing through path 4 of heat exchanger 1, the cold thus introduced into the system by the expansion of the minor portion of the air being imparted to the major portion of the air flowing through path 3 of heat exchanger 1 in heat exchange relation with the oxygen and the mixture of nitrogen and expanded air.

Line 51 leads from the top of the condenser or reboiler 40 and has a regulating valve 51a therein. This line communicates with an expander 53 which discharges by way of line 53a, into line 54, which as above described leads from the top of the low pressure stage 39 of the rectification system for the flow of nitrogen therethrough. Preferably, there is also provided a branch line 58 having a regulating valve 59 therein and leading from line 51 into a path 60 disposed in heat exchanger 21 in indirect heat exchange relation with the oxygen, nitrogen and air passing through the other three paths in this exchanger 21. A line 61 leads from path 60 back to line 51. Regulating valves 51a and 59, disposed in lines 51 and 58, respectively, regulate the portions of the

nitrogen stream flowing from the condenser 40 which are passed directly to expander 53 and indirectly through path 60 of exchanger 21. By the arrangement of lines hereinabove described, a minor portion of the total nitrogen introduced into the process passes from line 51, and, preferably, of the portion thus withdrawn, a minor portion, say about 10%, passes through line 58, path 60, and line 61, entering line 51 where it mixes with the remainder of the nitrogen withdrawn from the condenser 40. The portion of nitrogen passing through path 60 is warmed up by indirect heat exchange, and by mixing with the remainder of the nitrogen, the stream entering expander 53 is at a temperature sufficient to avoid condensation or formation of liquid nitrogen in the expander. In a preferred embodiment of the invention, from about 1% to about 15% by volume of the total nitrogen introduced into the process and containing incondensables, such as hydrogen, helium and neon, is passed through line 51, and of this quantity about 10% by volume passes through heating path 60 and about 90% by volume continues through line 51.

The nitrogen stream, refrigerated as a result of the expansion, flows from the expander 53 to a line 53a which meets line 54 conveying the nitrogen stream leaving the top of the low pressure section 39. The mixture then flows through heat exchanger 43 in indirect heat exchange relation with the nitrogen passing through this exchanger and thereafter flowing through reducing valve 44 into the top of low pressure section 39. From heat exchanger 43, the mixed nitrogen stream flows through line 55 into and through heat exchanger 47 where it flows in indirect heat exchange relation with the crude oxygen flowing therethrough to low pressure section 39. From the heat exchanger 47, the mixed nitrogen stream passes through line 56 into and through heat exchanger 35 where it passes in indirect heat exchange relation with air flowing into and from this exchanger by way of line 34. From the heat exchanger 35, the nitrogen stream containing incondensable gases removed from the high pressure stage, as hereinabove described, flows through line 36 into a compound valve 31, thence through path 22 or 23, as the case may be, of heat exchanger 21, through compound valve 28, through path 4 of heat exchanger 1, through compound valve 15, then through path 12 or 13 of heat exchanger 10, and finally through compound valve 14 to the atmosphere, the flow through paths 22 or 23 of heat exchanger 21, and 12 or 13 of heat exchanger 10, depending upon the setting of the valves associated with these exchangers.

One example of the operation of the process in the equipment shown in Fig. 2 is described below. It will be understood this example is given for purposes of exemplification only, and the invention is not limited thereto.

Air under pressure of about 75 pounds gauge and at a temperature of about 100° F. is supplied through line 16, valve 14, and line 17 to heat exchanger 10, flowing through path 12 in which it is cooled to a temperature of -80° F. Of the air flowing from valve 15, 7% by volume is expanded in engine 7, the pressure of the expanded air being about 5 pounds and its temperature about -215° F. This cold expanded air discharges into line 9 conveying nitrogen at a temperature of -200° F. from exchanger 21 to exchanger 1 and mixes with the nitrogen. The remainder of the air at a temperature of -80° F. passes through path 3 of exchanger 1 leaving this

path at a temperature of -195° F. It then flows through path 22 of exchanger 21, leaving this path at a temperature of -275° F. Substantially all moisture is removed in the form of frost in path 12 of exchanger 10. Little or no condensation takes place in path 3 of exchanger 1, and substantially all carbon dioxide is removed in solidified form in cooling path 22 of heat exchanger 21. The air from exchanger 21 flows through heat exchanger 35 in heat exchange relation with nitrogen and enters high pressure column 38 at a temperature of -278° F. and a pressure of 72 pounds.

Crude oxygen at a temperature of -280° F. and a pressure of 72 pounds leaves the base of column 38, flows through heat exchanger 41 where its temperature is reduced to -289° F. and upon flow through the pressure reducing valve 49 is flashed, entering low pressure column 39 at a temperature of -310° to -315° F. and a pressure of 5 pounds. Pure oxygen is withdrawn through line 57 at a temperature of -292.5° F. and a pressure of 5 pounds and flows through path 24, its temperature being increased to -200° F. The oxygen at this temperature enters path 2 of heat exchanger 1 and leaves this path at a temperature of -92° F. at which temperature it enters path 11 of heat exchanger 10 and is discharged from this path at a temperature of 90° F. and at a pressure of one pound.

Nitrogen at a temperature of about -286.5° F. and a pressure of 72 pounds in amount equal to 12.5% by volume of the total nitrogen introduced into the process is withdrawn through line 51. Of the nitrogen flowing through line 51, 10% passes through line 58 and heating path 60, its temperature being increased to -200° F. The remaining 90% of the nitrogen flows through valve 51a in line 51 and is mixed with the other 10% nitrogen, the temperature of the mixture being about -280° F. The nitrogen stream leaving the expander 53 is at a pressure of 5 pounds and a temperature of -315° F. The expanded nitrogen flows through line 53a and becomes mixed with nitrogen at a temperature of -315.5° F. and at a pressure of 5 pounds flowing through line 54. The resultant nitrogen stream passes through exchanger 43 in indirect heat exchange relation with nitrogen employed as reflux in column 39, its temperature being thereby increased to -306° F. while the temperature of the nitrogen flowing through line 42 (pressure of 72 pounds) and exchanger 43 is reduced to -300° F. This nitrogen, by expansion through valve 44, has its pressure reduced to 5 pounds and its temperature to -315.5° F. The nitrogen product of rectification then flows through heat exchanger 47 where its temperature is increased to -293° F. The crude oxygen stream flowing through exchanger 47 is thereby cooled from a temperature of -280° F. to a temperature of -289° F. The nitrogen then flows through exchanger 35 in heat exchange relation with the air, the nitrogen stream temperature being thereby increased to -279° F. at which temperature it enters the heat exchanger 21, flows therethrough and is thereby heated to -200° F. At the colder end of the heat exchanger 21, the nitrogen and oxygen streams have a weighted average temperature of nearly -282° F., while at this point the air is at a temperature of -275° F. A temperature difference of about 7° F. is, therefore, maintained. From heat exchanger 21, the nitrogen flows through heat exchanger 1 where it is heated to -92° F. It then enters and flows through heat exchanger

5

10

10, leaving this heat exchanger at a temperature of 90° F. and at a pressure slightly above atmospheric, say one pound gauge, and discharging into the atmosphere, thereby venting the in-

condensables, such as hydrogen, helium and neon, removed from the high pressure stage of the rectification system.

Upon reversal, as shown by dotted arrows and valve settings, which may take place every three minutes, the air flows through paths 13, 3 and 23, respectively, of heat exchangers 10, 1 and 21, and nitrogen, flows through paths 12, 4 and 22, respectively, of heat exchangers 10, 1 and 21. The flow is otherwise substantially the same and the temperature and pressure conditions remain the same. The nitrogen, in its flow through path 22 of heat exchanger 21, removes by sublimation, the carbon dioxide deposited in this path by the air during the preceding step. Likewise, the nitrogen, in its flow through path 12 of heat exchanger 10, removes from this path the frost deposited therein by the air during the preceding step. Thus, in the continued operation, upon each reversal, the nitrogen effects removal of the carbon dioxide and frost deposited in the paths through which the air has passed during the preceding step of the process.

Operating in accordance with this invention, which involves the intermediate non-reversing 30 heat exchanger 1, power requirements for each reversal period are diminished by an amount equal to the power required to compress to a pressure of 70 to 85 pounds gauge a volume of air corresponding to the volume of path 3 or 4 of heat exchanger 1; also, dilution of the compressed air stream with nitrogen and the nitrogen stream with air is minimized by an amount corresponding to the volume of gaseous fluid in the aforesaid paths 3 and 4. These results are made possible by maintaining the inlet temperature of the air to the intermediate exchanger 1 within the range of from -75° to -100° F., preferably from -75° to -85° F., and the exit temperature within the range of from -180° to -210° F., preferably from -195° to -205° F. Operating with these temperature conditions and the other conditions above pointed out, substantially all frost is removed from the air in exchanger 10, all carbon dioxide in exchanger 21 and little or no condensation takes place in exchanger 1. It will be understood that, while in the normal operation no reversal of flow takes place in exchanger 1, as a precautionary matter, to insure that the path through which the air flows remains in unobstructed condition, occasionally, say about once a week or month, flow through paths 3 and 4 in exchanger 1 may be reversed, so that the nitrogen stream passes through the path through which has previously passed the air, and vice versa.

The expressions "reversing the flow of air and nitrogen" and "reversal" are used herein in the sense commonly employed in this art, namely, to mean the switching of the flow of two streams, for example, the air and the nitrogen streams, so that upon each "reversal" the air flows through the path through which had previously flowed the nitrogen, and the nitrogen flows through the path through which had previously flowed the air.

Since certain changes may be made in carrying out the above process without departing from the scope of the invention, it is intended that all matter contained in the above description shall be

interpreted as illustrative and not in a limiting sense.

What is claimed is:

1. A process for producing oxygen by the liquefaction and rectification of air, which comprises, passing a stream of air through a path in a heat exchange zone containing at least three paths in heat exchange relation with each other, passing, respectively, streams of oxygen and nitrogen products of rectification through the other paths in said zone in heat exchange relation with the air passing therethrough, thereby cooling the air to a temperature such that substantially all moisture is removed therefrom, passing the air from the first zone through a path in a second zone in heat exchange relation with streams of oxygen and nitrogen products of rectification, cooling at least one of said streams flowing between said first zone and said second zone, the amount of cold thus introduced being adequate to compensate for cold losses resulting from the difference in enthalpy between the air introduced into and the products of rectification withdrawn from the process and for heat leaks into the system, passing the air from said second zone through a path in a third zone in heat exchange relation with streams of oxygen and nitrogen products of rectification, maintaining temperature conditions within said second and third zones such as to effect substantially no condensation of condensable constituents in the air in its passage through said second zone and the substantially complete removal of carbon dioxide from the air in its passage through said third zone, and periodically reversing the flow of air and nitrogen through their respective paths in the first and third zones, the air upon reversal flowing through the paths through which had previously flowed the nitrogen and the nitrogen flowing through the paths through which had previously flowed the air, whereby upon each reversal the nitrogen substantially completely removes the carbon dioxide deposited in said third zone and the frost deposited in said first zone during the preceding step of the process.

2. A process for producing oxygen by the liquefaction and rectification of air, which comprises passing a stream of air at about 70 to about 85 pounds gauge and a temperature of about 70° to about 110° F. through a path in a heat exchange zone containing at least three paths in heat exchange relation with each other, passing, respectively, streams of oxygen and nitrogen products of rectification through two other paths in said zone in heat exchange relation with the air passing therethrough, thereby cooling the air to a temperature such that substantially all moisture is removed therefrom, passing the air from the first zone through a path in a second zone in heat exchange relation with streams of oxygen and nitrogen products of rectification, cooling at least one of said streams flowing between said first zone and said second zone, the amount of cold thus introduced being adequate to compensate for cold losses resulting from the difference in enthalpy between the air introduced into and the products of rectification withdrawn from the process and for heat leaks into the system, passing the air from said second zone through a path in a third zone in heat exchange relation with streams of oxygen and nitrogen products of rectification, maintaining temperature conditions within said second and third zones such as to effect substantially no condensation of condensable constituents in the air in

its passage through said second zone and the substantially complete removal of carbon dioxide from the air in its passage through said third zone, maintaining the temperature difference between the temperature of the air leaving and the weighed average temperature of the nitrogen and oxygen entering said third zone so that it falls within the range of about 5° to about 10° F., and periodically reversing the flow of air and nitrogen through their respective paths in the first and third zones, the air upon reversal flowing through the paths through which had previously flowed the nitrogen and the nitrogen flowing through the paths through which had previously flowed the air, whereby upon each reversal the nitrogen substantially completely removes the carbon dioxide deposited in said third zone and the frost deposited in said first zone during the preceding step of the process.

3. A process as defined in claim 1 in which the air stream flowing between the first zone and the second zone is cooled.

4. A process as defined in claim 1 in which the air stream flowing between the first zone and the second zone is cooled and said cooling is effected by passing said air stream in heat exchange relation with a refrigerant.

5. A process for producing oxygen by the liquefaction and rectification of air, which comprises, passing a stream of air through a path in a heat exchange zone containing at least three paths in heat exchange relation with each other, passing respectively streams of oxygen and nitrogen products of rectification through the other paths in said zone in heat exchange relation with the air passing therethrough thereby cooling the air to a temperature such that substantially all moisture is removed therefrom, passing a major portion of the air from the first zone through a path in the second zone in heat exchange relation with streams of oxygen and nitrogen products of rectification, expanding the remaining minor portion of the air from the first zone, imparting the refrigeration thus produced to one of the streams flowing through the second zone to introduce an amount of cold adequate to compensate for cold losses resulting from the difference in enthalpy between the air introduced into and the products of rectification withdrawn from the process and for heat leaks into the system, passing said major portion of the air from said second zone through a path in a third zone in heat exchange relation with streams of oxygen and nitrogen products of rectification, maintaining temperature conditions within said second and third zones such as to effect substantially no condensation of condensable constituents in the air in its passage through said second zone and the substantially complete removal of carbon dioxide from the air in its passage through said third zone, and periodically reversing the flow of air and nitrogen through their respective paths in the first and third zones, the air upon reversal flowing through the paths through which had previously flowed the nitrogen and the nitrogen flowing through the paths through which had previously flowed the air, whereby upon each reversal the nitrogen substantially completely removes the carbon dioxide deposited in said third zone and the frost deposited in said first zone during the preceding step of the process.

6. A process for producing oxygen by the liquefaction and rectification of air, which comprises, passing air at about 70 to about 85 pounds gauge

and a temperature of about 70° to about 110° F. through a path in a heat exchange zone containing three paths in heat exchange relation with each other, flowing oxygen and nitrogen products of rectification, respectively, through the other two paths in said zone in heat exchange relation with the air, the air thus being cooled to a temperature of about -120° to about -150° F., the moisture being thereby removed from the air, refrigerating the air leaving the first zone to a temperature of about -125° to about -160° F. and passing the air thus refrigerated through a second zone in heat exchange relation with oxygen and nitrogen products of rectification, thereby cooling the air to a temperature of about -180° to about -210° F., thereafter passing the air through a path in a third zone in heat exchange relation with oxygen and nitrogen products of rectification, thereby cooling the air to a temperature of about -260° to about -280° F., the differential between the temperature of the air and the weighted average temperature of the oxygen and nitrogen at the colder end of said third zone being within the range of about 5° to about 10° F., and periodically reversing the flow of air and nitrogen through their respective paths in the first and third zones, the air upon reversal flowing through the paths in the said third and first zones through which had previously flowed the nitrogen and the nitrogen flowing through the paths in the said third and first zones through which had previously flowed the air.

7. A process as defined in claim 6 in which the air flowing from the first zone to the second zone is refrigerated by passing in heat exchange relation with ethylene.

8. A process as defined in claim 6 in which the reversal of flow of nitrogen and air through their respective paths in the first and third mentioned zones takes place at approximately three minute intervals.

9. A process for producing oxygen by the liquefaction and rectification of air which comprises passing a stream of air at about 70 to about 85 pounds gauge and a temperature of about 70° to about 110° F. through a path in a heat exchange zone containing at least three paths in heat exchange relation with each other, passing, respectively, streams of oxygen and nitrogen products of rectification through two other paths in said zone in heat exchange relation with the air passing therethrough, thereby cooling the air to a temperature such that substantially all moisture is removed therefrom, passing the air from the first zone through a path in a second zone in heat exchange relation with streams of oxygen and nitrogen products of rectification, cooling at least one of said streams, the amount of cold thus introduced being adequate to compensate for cold losses resulting from the difference in enthalpy between the air introduced into and the products of rectification withdrawn from the process and for heat leaks into the system, passing the air from the second zone through a path in a third zone in heat exchange relation with streams of oxygen and nitrogen products of rectification, regulating the flow of air, oxygen and nitrogen into and from said second and third zones so that the temperature within said second zone is such that substantially no condensation occurs and the temperature within the third zone is such as to effect substantially complete removal of carbon dioxide from the air in its passage through said third zone, passing the air

from the third zone to the high pressure stage of a two-stage rectification system, withdrawing a minor portion of the nitrogen containing incondensable gases from the high pressure stage, expanding the nitrogen thus withdrawn to cool the same, passing the expanded nitrogen in heat exchange relation with nitrogen and oxygen supplied as reflux to the low pressure stage and with air supplied to the high pressure stage, and periodically reversing the flow of air and nitrogen through their respective paths in the first and third zones, the air upon reversal flowing through the paths through which had previously flowed the nitrogen and the nitrogen flowing through the paths through which had previously flowed the air, whereby upon each reversal the nitrogen substantially completely removes the carbon dioxide deposited in said third zone and the frost deposited in said first zone during the preceding step of the process.

10. A process for producing oxygen by the liquefaction and rectification of air, which comprises passing air at about 70 to about 85 pounds gauge at a temperature of about 70° to about 110° F. through a path in a heat exchange zone containing three paths in heat exchange relation with each other, flowing oxygen and nitrogen products of rectification, respectively, through the other two paths in said zone in heat exchange relation with the air, the air thus being cooled to a temperature of about -120° to about -150° F., the moisture being thereby removed from the air, refrigerating the air leaving the first zone to a temperature of about -125° to about -160° F., and passing the air thus refrigerated through a path in a second zone in heat exchange relation with oxygen and nitrogen products of rectification, thereby cooling the air to a temperature of about -180° to about -210° F., thereafter passing the air through a path in a third zone in heat exchange relation with oxygen and nitrogen products of rectification, thereby cooling the air to a temperature of about -260° to about -280° F., the differential between the temperature of the air and the weighted average temperature of the oxygen and nitrogen at the colder end of said third zone being within the range of about 5° to about 10° F., passing the air from the third zone to the high pressure stage of a two-stage rectification system, withdrawing a minor portion of the nitrogen containing incondensable gases in the high pressure stage, expanding the nitrogen thus withdrawn to cool the same, passing the expanded nitrogen in heat exchange relation with nitrogen and oxygen supplied as reflux to the low pressure stage and with air supplied to the high pressure stage, and periodically reversing the flow of air and nitrogen through their respective paths in the first and third mentioned zones, the air upon reversal flowing through the paths in the said third and first zones through which had previously flowed the nitrogen and the nitrogen flowing through the paths in the said third and first zones through which had previously flowed the air.

11. A process for producing oxygen by the liquefaction and rectification of air which comprises passing air at about 70 to about 85 pounds gauge and a temperature of about 70° to about 110° F. through a path in a heat exchange zone containing three paths in heat exchange relation with each other, flowing oxygen and nitrogen products of rectification, respectively, through the other two paths in said zone in heat exchange relation with the air, the air thus being cooled to a temperature

of about -120° to about -150° F., the moisture being thereby removed from the air, refrigerating the air leaving the first zone to a temperature of about -125° to about -160° F. and passing the air thus refrigerated through a path in a second zone in heat exchange relation with oxygen and nitrogen products of rectification, thereby cooling the air to a temperature of about -180° to about -210° F., thereafter passing the air through a path in a third zone in heat exchange relation with oxygen and nitrogen products of rectification, thereby cooling the air to a temperature of about -260° to about -280° F., the differential between the temperature of the air and the weighted average temperature of the oxygen and nitrogen at the colder end of said third zone being within the range of about 5° to about 10° F., passing the air from the third zone to the high pressure stage of a two-stage rectification system, withdrawing from the high pressure stage about 1% to about 15% of the total nitrogen introduced into the process, said nitrogen containing incondensable gases, heating approximately 10% of the nitrogen thus withdrawn, mixing the heated nitrogen with the remaining 90% of the nitrogen thus withdrawn, thereby yielding a nitrogen stream having a temperature sufficiently high to avoid the formation of liquid nitrogen upon expansion of the nitrogen stream, expanding said nitrogen stream, passing the expanded nitrogen in heat exchange relation with oxygen and nitrogen supplied as reflux to the low pressure stage and with the air supplied to the high pressure stage, and periodically reversing the flow of air and nitrogen through their respective paths in the first and third zones, the air upon reversal flowing through the paths in the said third and first zones through which had previously flowed the air.

12. A process for producing oxygen by the liquefaction and rectification of air, which comprises passing a stream of air through a path in a heat exchange zone containing at least one other path in heat exchange relation with the air path, passing a stream of rectification product through the said other path in said zone in heat exchange relation with the air passing therethrough thereby cooling the air, passing the air from the first zone through a path in a second zone containing at least one other path in heat exchange relation with the air path, passing a stream of rectification product through said other path in said second zone, cooling at least one of said streams flowing between said first zone and said second zone, the amount of cold thus introduced being adequate to compensate for cold losses resulting from the difference in enthalpy between the air introduced into and the products of rectification withdrawn from the process and for heat leaks into the system, passing the air from the second zone through a path in a third zone containing at least one other path in heat exchange relation with the air path, passing a stream of rectification product through said other path in said third zone, maintaining temperature conditions within said second and third zones such that substantially no condensation occurs in said second zone and the substantially complete removal of carbon dioxide from the air takes place in its passage through said third zone, and periodically reversing the flow of air and rectification product through their respec-

tive paths in the first and third zones, the air upon reversal flowing through the paths through which had previously flowed the rectification product, and the rectification product flowing through the paths through which had previously flowed the air, whereby upon each reversal the rectification product substantially completely removes carbon dioxide deposited in said third zone during the preceding step of the process.

13. A process for producing oxygen by the liquefaction and rectification of air, which comprises passing a stream of air through a path in a heat exchange zone containing at least one other path in heat exchange relation with the air path, passing a stream of rectification product through the said other path in said zone in heat exchange relation with the air passing therethrough thereby cooling the air to a temperature such that substantially all moisture is removed therefrom, passing the air from the first zone through a path in a second zone containing at least one other path in heat exchange relation with the air path, passing a stream of rectification product through said other path in said second zone, cooling at least one of said streams during its flow, the amount of cold thus introduced being adequate to compensate for cold losses resulting from the difference in enthalpy between the air introduced into and the products of rectification withdrawn from the process and for heat leaks into the system, passing the air from the second zone through a path in a third zone containing at least one other path in heat exchange relation with the air path, passing a stream of rectification product through said other path in said third zone, maintaining temperature conditions within said second and third zones such that substantially no condensation occurs in said second zone and the substantially complete removal of carbon dioxide from the air takes place in its passage through said third zone, and periodically reversing the flow of air and rectification product through their respective paths in the first and third zones, the air upon reversal flowing through the paths through which had previously flowed the rectification product, and the rectification product flowing through the paths through which had previously flowed the air, whereby upon each reversal the rectification product substantially completely removes carbon dioxide deposited in said third zone and the frost deposited in said first zone during the preceding step of the process.

14. In apparatus for the separation of a gas mixture at low temperatures involving a reversing heat exchanger for removing by condensation from said gas mixture two condensable components thereof at different temperatures separated by an intermediate temperature range in which no component of said gas mixture is condensed, the improvement of said apparatus wherein said reversing heat exchanger comprises a series of three separate heat exchanger units serially connected for the flow of said gas mixture through said series of three units to effect the removal by condensation of one of said two condensable components in each of the two terminal units of said series, and valve arrangements associated with said terminal units adapted to alternate the fluid flows in said terminal units without alternating the fluid flows in the intermediate unit of said series in which intermediate unit no component of said gas mixture is condensed.
